L. R. N. CARVALHO

RECEPTACLE CLOSURE

Filed June 4, 1923

INVENTOR

LESLIE R. N. CARVALHO

BY *J. F. Rule*

HIS ATTORNEY

UNITED STATES PATENT OFFICE.

LESLIE R. N. CARVALHO, OF TOLEDO, OHIO, ASSIGNOR TO THE CLOSURE SERVICE COMPANY, OF TOLEDO, OHIO, A CORPORATION OF OHIO.

RECEPTACLE CLOSURE.

Application filed June 4, 1923. Serial No. 643,351.

To all whom it may concern:

Be it known that I, LESLIE R. N. CARVALHO, a citizen of the United States, residing at Toledo, in the county of Lucas and 5 State of Ohio, have invented new and useful Improvements in Receptacle Closures, of which the following is a specification.

My invention relates to a receptacle closure adapted for use with bottles, jars or 10 other containers. More particularly, it relates to a type of closure which when first applied to a container is secured in sealing position by attaching means which are destroyed or rendered ineffective when the container is first opened, but the closure itself 15 is adapted to be repeatedly used as a temporary closure, which is often desirable, while the contents of the container are being used up.

20 An object of the invention is to provide an improved closure or cap of this type which after being originally removed from the container may be repeatedly used to seal the container. For this purpose, the cap is 25 provided with attaching means for temporarily holding it in sealing position independently of the means by which the closure is originally attached to the container. By this provision, the closure cap can be repeatedly used and serves to tightly seal the 30 container after it has been originally opened. At the same time, the original sealing means having been destroyed, notice is given to the user that the closure as originally applied to 35 the container has been removed.

The present invention is in the nature of an improvement of the invention disclosed in my co-pending application, Serial Number 511,392, filed October 29, 1921.

40 In the accompanying drawings:

Figure 1 is a part sectional elevation of a container and closure therefor, embodying the principles of my invention.

Figure 2 is a section at the line II—II on 45 Figure 1.

Figure 3 is an elevation view illustrating the closure or cap being originally applied to the container.

Figure 4 is a similar view with the cap 50 secured in position on the container.

Figure 5 shows a modified form of container.

Figure 6 is a section at the line VI—VI on 55 Figure 5.

Referring particularly to Figures 1 to 4,

a closure or cap is shown applied to a container herein shown as a glass bottle. The cap as illustrated comprises a cover portion 10 and a flange portion 11 united by a seam 12. A gasket 13 of cork or other suitable material is fitted within the cap and when the cap is applied to the container forms an effective seal. When the cap is originally applied to the container, a tight seal is effected by applying a downward pressure 60 thereto at the seam 12, so that the gasket 13 is compressed as shown. The cap is secured in such position by bending the lower edge 14 inwardly to form a flange engaging a shoulder 15 on the neck of the container. 70

A score line 16 is formed in the flange 11 a short distance above the lower edge and extends the entire circumference of the cap, thereby providing a removable strip 17. One end of this strip may be extended to 75 form a finger piece 18. By grasping this finger piece, the rip strip 17 may be torn off, thereby permitting the cap to be removed from the container simply by withdrawing it in an upward direction. The 80 construction and operation as thus far described may be substantially the same as more fully set forth in my co-pending application above referred to.

After the original attaching means has 85 been destroyed by tearing off the strip 17, the cap may still be used as a temporary closure until the contents of the container have been used up. In order that the cap may be tightly held in place and form a 90 close seal during such use, the following construction is employed: The neck portion of the container is formed with bayonet slots or recesses comprising vertical portions 19 having lateral extensions 20 at their 95 lower ends. The cap is provided with inwardly projecting cooperating lugs 22 which may be formed by indenting the cap.

After the original locking strip 17 has 100 been torn off and the cap removed, the cap may be replaced and secured in sealing position by rotating it to carry the lugs 22 into the slot extensions 20. The extensions 20 provide shoulders 23, beneath which the lugs 22 engage, thereby firmly holding the cap 105 in position. The surfaces 23 are preferably slightly inclined, the inclination being sufficient to draw the cap down firmly into position as it is rotated and thus insure a tight seal. It will be observed that with this con- 110

struction, a resealing and locking means is provided by which the closure may be repeatedly used to seal the container. At the same time, the original removal of the closure necessitates the original securing means being destroyed, thereby giving notice that the container has been opened, thus preventing fraud and deception.

Figures 5 and 6 illustrate a modification 10 in which, instead of comparatively narrow slots 19, the width of the slots is increased so as to leave comparatively narrow vertical ribs 25. These ribs are undercut to form slots 20 and shoulders 23 as described in connection with Figures 1 to 4.

Modifications may be resorted to within the spirit and scope of my invention.

What I claim is:

1. The combination with a container, of a 20 cap therefor comprising an attaching means by which the cap is originally attached to the container, said attaching means being separable from the body of the cap to permit removal of the cap, a second attaching 25 means by which the cap may be attached to the container after the original attaching means has been removed, said second attaching means being maintained out of attaching position during the original positioning 30 and attachment of the cap to the container.

2. The combination with a container, of a cap therefor comprising an attaching means by which the cap is originally attached to the container, said attaching means 35 being separable from the body of the cap to permit removal of the cap, a second attaching means by which the cap may be attached to the container after the original attaching means has been removed, said second 40 attaching means comprising interlocking parts carried by the cap and container respectively and maintained out of interlocking relation during the original positioning and attachment of the cap to the container.

45 3. The combination with a container, of a cap therefor comprising an attaching means by which the cap is originally attached to the container, said attaching means being separable from the body of the cap 50 to permit removal of the cap, a second attaching means by which the cap may be attached to the container after the original attaching means has been removed, said second 55 attaching means comprising interlocking surfaces on the cap and container respectively, said surfaces being held out of engagement during the original placing and attachment of the cap to the container and brought into operative relation by a rotative 60 movement of the cap on the container.

65 4. The combination of a container comprising a neck, a closure cap therefor comprising a flange portion extending downward to surround the neck, means for originally securing the cap in position, a second

securing means for holding the cap in position on the container after it has been removed, said second securing means comprising interengaging projections on the cap and container respectively, said projections 70 being arranged to be held out of contact during the original placing and securing of the cap on the container.

5. The combination of a container comprising a neck, a closure cap therefor comprising a flange portion extending downward to surround the neck, means for originally securing the cap in position, a second securing means for holding the cap in position on the container after it has been removed, said second securing means comprising a bayonet slot in the neck of the container, said slot including a vertical portion 75 extending downward from the lip of the container and a laterally extending portion, and a detent on the cap which moves downward in said vertical portion of the slot during the original placing of the cap and is maintained in said vertical portion of the slot while the cap is originally secured, said 80 detent being arranged to enter said lateral portion of the slot for locking the cap in position after the cap has been originally removed from the container and replaced.

6. The combination of a container comprising a neck portion formed with an annular shoulder, a cap therefor comprising a top cover portion and a flange portion, the flange portion including a removable strip having its lower edge turned inward beneath said annular shoulder for originally securing the cap to the container, a second securing means comprising a detent formed in the cap, and a cooperating bayonet slot formed in the neck of the container, said slot comprising a vertical portion to receive said detent during the original placing and securing of the cap on the container, and a lateral extension to receive said detent and lock the cap in position when replaced on the container after said strip has been removed.

7. The combination of a container, a closure cap therefor, said cap comprising attaching means by which the cap is originally secured in position on the container, said attaching means being separable from the body of the cap to permit removal of the cap, said container and cap being provided with interlocking means comprising a bayonet slot and lug by which the cap may be repeatedly attached to and removed from the container, said interlocking means being arranged to permit the cap to be originally placed on the container and secured by said attaching means without bringing said slot and lug into interlocking engagement.

8. The combination of a container having a neck portion formed with a bayonet slot and an annular shoulder surrounding the

- neck below said slot, said slot comprising a vertical portion extending downward from the mouth of the container and a lateral extension, a cap comprising a cover portion 5 and a flange portion, the latter being scored adjacent its lower edge to form a detachable strip, said strip being bent inward beneath said shoulder for originally securing the cap on the container, whereby when said strip 10 is detached the cap may be removed from the container, said cap having a lug cooperating with said bayonet slot and forming therewith an attaching means by which the cap may be repeatedly attached to the container, said lug being retained in said vertical portion of the slot during the original positioning and securing of the cap on the container.
9. The combination with a container, of 20 a cap therefor, means for attaching the cap to the container, and a second attaching means maintained out of operative position during the positioning and attachment of the cap by said first mentioned attaching means.
10. The combination with a container, of 25 a cap therefor, means to attach the cap to the container, said cap being so constructed that it may be brought by a straight downward movement into position to be attached
- by said means, and a second attaching means maintained out of attaching position during the positioning and attachment of the cap by said first attaching means.
11. The combination with a container, of 30 a cap therefor, means to attach the cap to the container, said cap being so constructed that it may be brought by a straight downward movement into position to be attached by said means, and a second attaching means 35 maintained out of attaching position during the positioning and attachment of the cap by said first attaching means, said second attaching means being brought into operative position by a rotative movement 40 of the cap on the container.
12. The combination with a container, of 45 a cap therefor, means for attaching the cap to the container, and a second attaching means maintained out of operative position 50 during the positioning and attachment of the cap by said first mentioned attaching means, said first mentioned attaching means comprising a part removable from the body of the cap for detaching the cap from the receptacle.

Signed at Toledo, in the county of Lucas and State of Ohio, this 1st day of June, 1923.

LESLIE R. N. CARVALHO.
